Primary Examiner — Patricia Palasik(74) *Attorney, Agent, or Firm* — John D. Veldhuis-Kroeze; Westman, Champlin & Koehler, P.A.(57) **CLAIM**

The ornamental design for a numerical control machine center, as shown and described.

DESCRIPTION

FIG. 1 is a perspective view of a numerical control machine center showing our new design.

FIG. 2 is a front elevational view of the numerical control machine center.

FIG. 3 is a rear elevational view of the numerical control machine center.

FIG. 4 is a left side view of the numerical control machine center.

FIG. 5 is a right side view of the numerical control machine center; and,

FIG. 6 is a top plan view of the numerical control machine center.

The numerical control machine center of the present design is a large-sized heavy item, and the bottom view forms no part of the claimed design and is therefore omitted.

The broken lines in the drawings depict unclaimed environmental subject matter.
